UNITED STATES PATENT OFFICE

JAMES WILLARD HARVEY, OF WINTHROP, MAINE

BOAT CONSTRUCTION

Application filed January 25, 1932. Serial No. 588,565.

My invention relates particularly to what are commonly termed cabin cruisers.

The main object is to provide a construction adapted to small power boats which can be built and operated economically.

In boats of small size, for instance, sixteen to twenty feet overall, it is obvious that the space available for a cabin is very small. Furthermore, in light draft boats which are most desirable for cruising in lakes and along the shore the head room provided by the ordinary construction is very limited. It is not feasible in such constructions to build a cabin with sufficient head room because it adds to the expense and makes the boat top heavy and unstable in a wind. Furthermore, to keep the lines attractive in appearance the cabin must be quite low. The cabin should also be low enough to permit the helmsman to have clear vision over the top of the cabin. As a result of these limitations the ordinary small cabin cruiser is cramped and uncomfortable and provides very poor accommodation for cooking or otherwise enjoying the indoor comforts so desirable when cruising.

I have accordingly designed a boat having a cabin well proportioned in appearance and stability which can be provided with bunks, galley equipment and so forth, and yet when desired the head room can be extended for the whole or part of the length of the cabin. The construction is particularly adapted to be combined with a windshield and canopy top for protection of the cockpit.

The construction is especially designed for use with a motor installation of the type set forth in my Patents #1,786,997, #1,824,887, #1,850,948 and #1,840,949, which permits the operation of the boat with safety in shallow water and at the same time avoids difficulties inherent with propellers of the conventional inboard type and as well as the disadvantages of the outboard type drive.

Fig. 1 is a side view of one form of construction embodying my invention, showing the cabin in the normal cruising condition and also showing the windshield and canopy top. The cabin extension is shown in dotted lines, in the raised position.

Fig. 2 is a plan view omitting the canopy top.

Fig. 3 is a transverse sectional view showing the windshield and with the cabin roof in the cruising position.

Fig. 4 is a transverse sectional view showing the cabin roof with the extension raised.

Fig. 5 is a longitudinal sectional view showing the cabin top raised.

Fig. 6 is a longitudinal sectional view and showing a modification of the windshield and cabin arrangement.

Fig. 7 is a fragmentary plan view of the same.

Fig. 8 is a cross section showing the roof in cruising position.

Fig. 9 is a side view showing in dotted lines another arrangement of motor.

For appreciation of the problems involved although without intending to limit the invention to a boat of any specific dimensions, it may be stated that the boat illustrated is intended to be approximately 18' long and of shallow draft. It has been designed to afford a maximum cabin accommodation together with a good sized cockpit. Such a boat can be used with substantially any type of inboard or outboard motor but I prefer to employ a motor and casing 10 of the type set forth in my former patents mounted near the stern in a propeller adapted to be readily withdrawn inside the casing.

The cabin 11 should have a low main roof 12 extending only a comparatively short distance above the deck 13. The forward end 85 of the cabin preferably has an extension 14 with a roof which is inclined. This inclined extension 14 provides some head room forward of the main cabin and access to the bow beneath the deck and reduces the head wind 90 resistance. The aft end of the cabin is provided with walls 15 and doors 16 so that the cabin may be entirely closed if desired. Any suitable type of windows or ports and ventilation may be provided.

The front cabin extension serves as a convenient place for toilet accommodations.

The cockpit may be provided with suitable sitting accommodations in the usual manner. Preferably the steering wheel 17 and other 100

control instruments are mounted on the wall 15. Provision may be made for enclosing the cockpit if desired.

In the somewhat larger boats a bow cockpit 5 may be provided forward of the cabin.

A tilting rudder of the type set forth in my application #561,101, may be employed if desired or the motor propeller may be used for steering in any well known manner.

10 The cabin accommodations may of course be arranged to suit individual desires within the limits of the available space. It is highly desirable, however, to provide a pair of berths such as 20, one on each side and these 15 may be hinged as at 21 along their outer edges so as to permit them to be swung up against the sides of the boat leaving the cabin floor clear. The ends of the berths extend forward beneath the deck 13 and the cabin extension 14 so as to leave space at the rear end 20 of the cabin for a stove 22 and a sink 23 and the usual ice-box and cupboard or locker accommodations.

25 The additional head room is provided by forming the central part 25 separate from the rest of the roof and mounting it in such a manner that it may be raised conveniently so as to provide convenient space at least over the rear end and the central portion of the 30 cabin so as to facilitate work around the sink or stove and movement longitudinally between the berths, and to provide free space in the center when the berths are swung back out of the way. This central roof section is 35 normally supported in a suitable manner, for instance, on the side timbers 26, and may be provided with weather strip closures 27 covering the joints. End supporting blocks such as 26' may be employed.

40 The sides of the cabin extension in the form shown consist of two longitudinal sections 28 and 29. The lower section 28 is hinged at 30 to the timber or beam 26 extending longitudinally of the boat. The section 29 is hinged 45 at 31 to a longitudinal timber 32 forming a part of the extension roof structure. The two sections 28 and 29 are hinged together along the line 33. These three hinges may conveniently be what is commonly termed a piano 50 type hinge. When the extension roof is down the side sections may be conveniently suspended, for instance, by a number of hooks 34.

To secure the additional head room it is 55 merely necessary to lift the roof section 25 whereupon the side sections 29 and 28 swing into place and may be held in elevated position in any suitable manner, as for instance, by means of bolts 35 or other suitable latch mechanism. These side sections 28 and 29 60 may be provided with windows or ventilating passages in any well known manner.

65 Each end of the roof extension may be closed in any suitable manner, as for instance, by means of an end piece 36 hinged at 37. When the extension is down this end piece 36

will lie between the sections 29 and the roof. When the extension is up this end piece 36 will be lowered into place and will serve to hold the sides in the upright position the lower edge of 36 may be then supported by block 70 26'. The extension when raised and the front end down, may be held by any suitable bolt or latch 38. The aft end of the extension may be closed by means of a member 40 which in the preferred construction may constitute a 75 windshield supported by the canopy top 41.

This canopy top 41 may be supported by frame members 42 and posts 43.

I also prefer to provide the windshield sections 44 on each side of the central shield 80 40 and all of these windshield sections may be supported in any convenient manner. The section 40, however, is preferably hinged at 45 at the top so that it can be swung upwardly and to the rear leaving greater head room for 85 entrance to the cabin when the extension roof is up.

90 Preferably this windshield arrangement is a short distance forward of the walls 15 and doors 16 so that a ledge 46 is provided on each side of the cabin convenient for the helmsman to deposit maps, instruments, etc. These ledges 46 constitute parts of the roof of the cabin on each side of the hatches 47 which are hinged so that they can swing upwardly 95 and outwardly to facilitate entrance to the cabin. These hatches may be supported on battens 48 on the lower edge of the windshield 40 and may also rest on the upper edges of the doors 16. The hatches may themselves 100 have battens or stops 49 for the doors 16.

I also preferably provide side windshield sections 50 extending between the canopy top and the roof of the cabin.

105 It will be obvious from the foregoing that the doors 16 may be opened for entrance to the cabin at any time. The various doors may be mounted to slide instead of swing where there is suitable space for such sliding action.

110 The hatches 47 can be raised at any time for ventilation which is especially desirable immediately above the stove 22. When the roof extension is raised its rear edge interlocks beneath the front edge of the canopy top 41. By raising the hatches 47 and the windshield 40 full head room is provided from the cockpit into the cabin.

115 When the extension roof is up it will be obvious that it may be closed at the rear by the windshield 40 but that it does not obstruct the vision of the helmsman through the windshield sections 44 at each side.

120 When the extension roof is down in what might be termed the normal cruising position there is still head room enough in the cabin to permit its use in the customary manner since none of the parts involved in the extension construction provide any substantial obstruction.

It should be understood that the construction and arrangement may be modified in detail within my invention, for instance in Figs. 6 and 7. I have shown the construction in which the windshield section 40' is normally inclined and supported at its upper end by pivots 51 adapted to slide fore and aft in guides 52. In this case the lower edge of the windshield normally rests on the extension roof 25 and the doors 16 are arranged on the same transverse plane as the rear edge of the roof extension. By loosening the hinge pins 51 and sliding the shield to the rear slightly the lower edge of the windshield will clear the roof section 25 so as to permit the center roof section to be raised. The windshield section can then be slid back into the dotted position shown in Fig. 6 serving as a closure for the extension. In this case the sides 53 of the cabin are extended rearwardly to obtain extra space in the cabin in rear of the doors. Such a construction may be desirable when an inboard motor is used in which case the extra space in the center of the cockpit is more important than in the cabin.

In Fig. 9 I have shown an inboard motor 55 with reverse gear 56 and the propeller 57 is carried by a shaft housing 58 and plate 59 which is mounted in an opening in the casing 60. The housing 58 may be hinged at 61 to permit retraction of the propeller into the casing. The plate 59 may be suitably held down to close the opening in the bottom of the casing. The propeller is driven by the motor through suitable clutch and gear trains which permit the propeller to be retracted for inspection, repair, etc. This arrangement affords excellent balance in the boat and a horizontal propeller driving in solid water beneath the plate, at the same time obviating inaccessibility and stuffing box leakage commonly encountered when inboard type motors are used. The propeller thus mounted can tilt to clear bottom obstructions and permits replacing shear pins, removing weeds, oiling, etc. with ease and safety from inside the boat while afloat.

The motor being set level on the main framework aft the longitudinal center of the boat is in the best position to insure stability, easy running and properly distributed load, there being no driving strain on the transom and no long inclined shaft through the boat bottom.

The bottom plate may be seated against a rubber gasket and may be secured by means of a latch or frangible fastening or simply clamped in the bottom of the well for operation in deep waters.

Although the canopy top and windshield are important features in the preferred form of my invention it should be understood that many of the advantages can be had with a

construction as herein described without the canopy top and windshield.

I claim:

1. A boat cabin having an extensible roof section, side sections and an end section movable with the roof section and a canopy top having a windshield serving as an oppositely located end section for the extensible roof section. 70
2. A boat cabin having a roof and canopy with a windshield in the fore part of the canopy above the roof of the cabin and an extensible top for the cabin closed aft by the windshield when the top is elevated. 75
3. A boat cabin having a windshield above its aft end and an extensible top adapted to interlock with the windshield when the top is raised. 80
4. A boat cabin having a main roof, a canopy extending forwardly over the aft end of the roof, a windshield connecting the canopy and the roof of the cabin, an extensible roof section in front of the windshield, the end of the roof aft the windshield being removable. 85
5. A boat cabin having an extensible central roof section adapted to be lifted above the main roof of the cabin, a canopy above the level of the main part of the roof, means for lifting the central section into cooperation with the canopy and means for closing the opening forward of the central roof section. 90
6. A boat cabin having a roof and an extensible top section connected to the cabin roof by folding sides, and removable sections for closing the forward and aft openings between the top section, the sides and the roof formed by lifting the top section. 100
7. A boat cabin having main roof sections, an extensible top section, folding members connecting the opposite edges of the top section with the adjacent edges of the main sections and end sections adapted to fill in and close the openings beneath the ends of the top section when the top section is raised. 105
8. A boat cabin having a main roof and a movable central part of its roof formed separate from the main roof, and side sections hinged to the central part and connected to the edges of the main roof. 110
9. A boat construction comprising a cabin having an extensible roof section, side sections hinged to said extensible section, and a front end section hinged to the extensible section and adapted to fold between the side sections and the roof section. 120
10. A boat construction comprising a cabin having a main roof with a central extensible roof section, a windshield at the rear of the roof having a central section to close the end of the extensible section when the latter is raised and having a side section on each side of the central section unobstructed by the extensible section. 125

11. A boat construction comprising a cabin having a roof with an extensible central roof section, a canopy top connecting with said roof section when it is elevated, and wind-shield sections above the main roof on each side of the extensible section. 90
12. A boat construction comprising a cabin having a central extensible roof section and two hinged hatch sections in rear of the extensible section, hinged means for supporting the central section and vertical doors for entrance to the cabin beneath the hatch sections, the hatch sections and extensible roof sections being separately movable. 100
13. In a boat construction having a store therein, a cabin, a windshield near the rear thereof, an entrance door for the rear of the cabin and a removable hatch for the roof in rear of the windshield providing ventilation for a stove within the cabin and an extensible roof section forward of the windshield providing extra head room in the center. 110
14. A boat construction having a deck and comprising a cabin extending a short distance above the deck, a berth hinged to one side of the boat and adapted to swing up under the edge of the deck, a portion of the roof of the cabin being extensible and provided with sides and ends to form extra head room along the center of the boat. 120
15. A boat cabin having a main roof and an extensible roof section, longitudinal beams carried by the main roof for supporting the side edges of the extensible section in a cruising position and side sections hinged to the lower edges of said beams for supporting the extensible roof section in an elevated position. 130
16. A boat construction having a deck and comprising a cabin having a main roof projecting above the deck and having a vertically movable central roof section, hinged members connecting the movable section with the main section, berths supported along the sides of the cabin and extending forwardly beneath the deck, and a door leading to the space beneath the central roof section and between the berths. 140
17. A boat having a cabin with a vertically movable roof section, folding sides for supporting the movable roof section and an end section hinged to the movable roof section and adapted to be moved into position between the folding sides to hold them in place when the movable roof section is elevated. 150
18. In a boat construction having a deck and a cabin with a stove and lockers in the rear and a forward extension, a berth on each side of the cabin extending forwardly under the deck, said cabin having space in rear of the berths for the stove and lockers and a vertically extensible central roof section for providing increased head room. 160
- around the stove and between the berths when desired. 170
19. A boat having a cabin with a roof having an opening in the top, longitudinal beams depending from the roof along the sides of the opening, a vertically movable roof section adapted to close said opening, and folding sides connecting the lower edges of said timbers and the edges of the movable roof section and adapted to fold inwardly when the movable roof section closes the opening. 180
20. A boat having a cabin with a roof and having an opening in the roof, main beams depending from the roof along the edges of the opening, a vertically movable roof section having beams depending from its edges and adapted when in lowered position to overlap the edges of the main roof beams, folding sides connecting the main roof beams and the beams of the movable roof section and means for holding the sides and the movable roof section in elevated position. 190
